WALL SUBJECTED TO HIGH TEMPERATURES

Alfred Ossolin, Shaker Heights, Ohio

Application November 13, 1936, Serial No. 110,770

5 Claims. (Cl. 266—39)

This invention relates to metal walls subjected to high temperatures. Side walls of blast-furnace slag ladles and covers for molten metal ladles are examples of such walls. One of the objects is to construct a wall that will not easily crack or break when subjected to high temperatures.

Various examples of the invention are illustrated by the accompanying drawings, in which:

Figure 1 is a partial top view of a slag ladle embodying the features of the invention.

Figure 2 is a sectioned elevation of this ladle.

Figures 3 and 4 are sections taken respectively from the line III—III and IV—IV in Figure 2.

Figure 5 is a partial view of the outside of the ladle taken from the line V—V in Figure 2.

Figure 6 is a partial view of the top of a slag ladle cover employing the features of the invention.

Figure 7 is a cross-section taken from the line VII—VII in Figure 6.

Figure 8 is a partial top view of a slag ladle cover embodying a modification of the principles shown by Figures 6 and 7.

Figure 9 is a cross-section taken from the line IX—IX in Figure 8.

The blast-furnace slag ladle constituting the first example of the invention has a solid metal bottom 1 and a side wall 2 that is provided with a series of lengthwise extending slots 3. Each of these slots is filled with a plurality of parallel metal strips 4. These strips extend edgewise toward the inside of the ladle, their rear edges being fixed to the wall 2 by welding metal deposited through openings 5 formed in the wall at the bottoms of the recesses 3.

A blast-furnace slag ladle is ordinarily made with its walls completely solid. In service, it is subjected to heavy stresses resulting from its tendency to warp under the effects of thermal expansion and contraction. Due to the fact that its walls are solid and rigid, pieces often break out, leaving holes which must be repaired. The ladle disclosed above is not so subject to this trouble. Its bottom 1 is solid because its shape is such as to enable it to withstand stresses encountered in

service, it being understood that it is usually the side wall of a ladle that is particularly inclined toward breakage. In the case of the disclosed ladle, this side wall is composed primarily of metal strips or laminations, which are anchored only at their rear edges whereby they are capable of moving individually to at least some extent and to thus individually accommodate expansive and contractive effects. Due to the fact that each strip contracts and expands as an individual unit,

neither single stresses nor stress concentrations can build up to values sufficiently large to cause the strips to tear from their proper positions. While retaining the strength of a solid wall the side wall of the disclosed ladle is sufficiently flexible to prevent its being damaged in service.

A second example of the invention is the cover for a metal ladle. This cover comprises a relatively thin wall 6 of suitable shape. A plurality of metal strips 7 are fixed to the high temperature side of this wall so as to extend edgewise toward the high temperature, this being done by the deposition of welding metal through openings 8 formed in the wall 6, so as to unite the edges of the strips 7 remote from the high temperature. A depending tapering ring 9 is welded around the outside of the group of laminations provided by the strips 7 so as to render the cover more serviceable. It is to be understood that the strips 7 are cut in such lengths as to permit them to fill the circular area defined by this ring 9.

This ladle cover possesses the same advantages as are possessed by the previously described slag ladle. That is to say, the metallic wall that must resist high temperatures is composed primarily of a number of small pieces of metal, none of which are of sufficient size to result in breaking stresses being produced upon temperature variations.

The modified ladle cover consists in a wall 10 of suitable shape, which mounts a single metal strip 11 arranged in the form of a coil. Bars 12 may be welded transversely to the coil of strip and their opposite sides then welded to the wall 10 by the deposition of welding metal through holes 13 in this wall, which register with the bars. The ring 14 shown is the same as the ring 9 and accomplishes the same purpose. This modification is further characterized in that metal sheets 15 are loosely laid on top of the edge of the coil of metal strip 11, and insulating material 16 is placed in the space between the wall 10 and these sheets 15, the latter retaining this material in place.

Although flat strip has been illustrated as comprising the pieces of metal, it is to be understood that relatively thin pieces of any shape may be used, these being arranged to extend edgewise toward the high temperature side of the wall. The fundamental idea is the use of a number of relatively thin pieces which extend edgewise from the high temperature side of the wall and which are individually so weak that even when they tend to warp due to temperature changes they do not possess sufficient strength to tear themselves loose.

I claim:

1. A wall subjected to high temperatures, that is characterized by including a plurality of relatively thin metal pieces arranged with their edges toward the high temperature and provided with mounting means permitting their individual movement to at least some degree.
2. A wall subjected to high temperatures, that is characterized by including a supporting wall and a plurality of adjacent relatively thin metal pieces extending edgewisedly from the high temperature side of said wall toward the high temperature, said pieces being connected to said supporting wall at their edges remote from the high temperature but being otherwise free to move individually when subjected to thermal contractive and expansive effects.
3. A wall subjected to high temperatures, that is characterized by including a supporting wall and a plurality of adjacent relatively thin metal pieces extending edgewisedly from the high tem-

perature side of said wall toward the high temperature, said wall having openings registering with the adjacent edges of said pieces and through which welding metal is deposited to connect the last named edges to said wall, said pieces being otherwise individually free to accommodate thermal expansion and contraction.

4. A ladle having a metal side wall provided with a plurality of lengthwisedly extending recesses and a plurality of metal strips fixed in said recesses and substantially filling the same, said strips being arranged in edgewise relationship respecting the interior of the ladle and being free for at least limited individual movement upon thermal expansion and contraction of the same.

5. A wall subjected to high temperatures, that is characterized by including a supporting wall and a coil of metal strip fixed to the high temperature side of said wall by its edge.

ALFRED OSOLIN.
